ROOFING

Application filed June 27, 1927. Serial No. 201,808.

My invention is an improved water-proof roofing and comprises an inter-locking composition shingle that may be used as the sole roofing material or in combination with tile. When used with tile each of the composition shingles has fixed thereto a tile of such form that when the roof surface is covered with the inter-locking shingles the tiles fixed thereto will form the outer exposed surface. Tile roofs as now constructed are laid over a complete water-proof roof consisting of tarred paper and tar or other similar materials. The provision of the water-proof under-roof beneath the tiles is necessary on account of the fact that water finds its way between the tiles in a heavy down-pour of rain and especially when the wind gets beneath the edges of the tiles and raises them and drives the rain into the spaces between adjoining tiles. Commonly tiles are laid, as in the mission type of tiling, with side and end overlap to prevent as far as possible the entrance of water, a measure that was absolutely necessary in former days when the modern water-proofing materials of which the under-roofs are now constructed were unknown. The overlapping of the tiles and the relatively great thickness of the tiles heretofore necessary to give them sufficient strength results in a roof of immense weight, and such a roof can be laid only on a building having a roof structure and supporting structure built at a cost and having a degree of strength that are necessary for no other purpose than merely to support a roof of this character. The necessity of making the roofs of modern structures absolutely water-proof and the provision for that purpose of a complete water-proof roof beneath the tile makes it a matter of no importance whether the tiles be overlapped in such a way as to minimize as far as possible the entrance of water or be laid without extensive or any over-lap. The ultimate reliance for water exclusion is the under-lying water-proof roof, and as the under-lying roof is capable of carrying off all of the water it is immaterial whether a greater or lesser amount is carried off by it. Therefore when tile is used as part of my improved

roofing I prefer to dispense altogether with the overlap at the side edges, simply bringing the tiles together with the side edges abutting. At the upper and lower ends the tile may overlap to preserve the usual appearance of tile roofing or they may simply abut at the upper and lower edges.

In the drawings:

Figure 1 is a view of one of the base units before the marginal sections of the tar paper or other composition of which it is made are folded over the central flat section.

Figure 2 shows the base unit with the marginal sections folded over the central section.

Figure 3 is a view of a base section with a tile attached thereto.

Figure 4 is a view of four of the base units assembled in inter-locking engagement but without tiles attached thereto.

In Figure 5 I show eight units assembled, each unit comprising a base unit with a tile attached thereto.

Figure 6 is a view on a transverse section of the structure shown in Figure 3, the section being parallel to the short sides of the tile 7 and midway between them.

The form of the blanks from which the inter-locking shingles are made is shown in Figure 1 and consists of a central parallelogram with surrounding marginal sections 2, 3, 4 and 5. As indicated in Figure 2 the section 4 is folded over the front or top of the central section, i. e. over the side of the central section that lies uppermost as represented in the drawings which side lies uppermost when the shingle is in position upon the roof. The section 3 is then folded over the same side of the central section. The line upon which the section 3 is folded forms a slightly acute angle with the line upon which section 4 is folded and a correspondingly obtuse angle with the line upon which section 2 is folded, and the line upon which section 5 is folded is parallel to that upon which section 3 is folded, the fold lines for sections 2 and 4 being also parallel. Marginal sections 2 and 5 are folded over the back of the central section 1, i. e. over the side which lies underneath as the shingle lies upon the roof

structure. Figure 4 shows four of these base units assembled in inter-locking engagement as when laid upon a roof structure to which they may be fastened by means of 6 nails at any convenient points. Assuming that the unit *c* is first placed in position, the unit *d* is placed beside unit *c* with the fold 2 of *d* interlocking with fold 4 of *c* and fold 3 of *d* underneath fold 3 of *c*. Unit *a* is then 10 placed above *c* with the fold 5 of *a* interlocking with fold 3 of *c*, after which unit *b* is placed beside *a* with the fold 3 of *b* beneath fold 3 of *a*, fold 2 of *b* interlocking with fold 4 of *a* and fold 5 of *b* interlocking with fold 15 3 of *d*. As so assembled the base units constitute a complete water-proof roof and may be so used. In Figure 3, however, I have shown a tile, 7, fixed to the base. The upper and lower flaps 3 and 5 are made at an oblique 20 angle with the side edges 2 and 4; for otherwise the upper edge of each unit, lying inside of the upper fold 3 of the unit at the left, would be stepped down with respect to that unit by an amount equal to the thickness of 25 the material. The rows of units would not be parallel to the ridge and eaves, but would be inclined thereto.

As above stated the base units may be constructed of paper impregnated with asphalt 30 or tar or of asbestos or other fireproof composition and the tile may be attached securely to the base unit by means of asphalt tar or similar suitable substance. The tiles 7, as shown in Figure 5, are of a width sufficient 35 to cover the roof surface with their side edges abutting without overlap, and are fixed to the base units with the edges of the tile projecting beyond the two edges of the base unit upon which the marginal sections of the 40 base unit are folded under, i. e. away from the tile. The other two edges of the base unit project beyond the edges of the tile thereby leaving the folded marginal sections 3 and 4 exposed for convenient engagement 45 with the adjoining units when the roof is laid. I have shown the tile 7 in Figures 3 and 5 of such length that in assemblage the lower edge of each tile laps over the upper edge of the adjoining tile in the next row 50 below, the yielding structure of the base units permitting the tiles to be disposed in this way. As above stated, however, the tiles may simply abut at the lower and upper edges as at the side edges.

55 The angle between the fold lines of marginal sections 3, 5 and the fold lines of sections 2, 4 is sufficient to permit the units to be laid in rows perpendicular to their side edges. The amount of angularity will therefore depend on the thickness of the material 60 of which the base units are constructed, as it is the thickness of the material that determines the extent to which the upper edge of each unit is out of alinement with the 65 upper edges of the adjoining units.

I claim:

1. A roof comprising a plurality of base units, each of said units having a central flat section and marginal sections folded over said central section, said marginal sections of said units overlapping in interlocked engagement, and a tile secured to each of said base units. 70

2. A roof comprising a plurality of base units, each of said units having a central flat section and marginal sections folded over said central section, said marginal sections of said units overlapping in interlocked engagement, and a tile secured to each of said base units, the tile on each of said base units 75 projecting beyond two of the adjoining edges of the base unit and the other two adjoining edges of said base unit projecting beyond the edges of the tile. 80

3. A roof comprising a plurality of units, each unit having a central flat section and marginal sections folded over said central section, some of said marginal sections being folded over one side and the others over the other side of said central section, said 90 units being laid edge to edge with their folded marginal sections in interlocking engagement, and a tile fixed to each of said units. 95

4. A roof comprising a plurality of quadrilateral units, each of said units having a central flat section and marginal sections folded over said central section, the marginal sections at opposite sides being reversely folded, said units being laid edge to edge with their folded marginal sections in interlocking engagement, and a tile fixed to each of said units. 100

5. A roof comprising a plurality of base units, each of said units having a central flat section and marginal sections folded over said central section, said marginal sections of said units overlapping in interlocked engagement, and a tile secured to each of said base units, the tile on each of said base units 105 projecting beyond two of the adjoining edges of the base unit and the other two adjoining edges of said base unit projecting beyond the edges of the tile, the marginal sections on the edges of said base unit which project beyond said tile being folded over the side of said base unit to which said tile is fixed and the other marginal sections being folded over the opposite side of said base unit. 110

6. A roof comprising a plurality of quadrilateral units, each of said units having a central flat section and marginal sections folded upon each edge thereof, the marginal sections of said units overlapping in interlocking engagement, the side marginal edges of each unit being parallel to each other and normal to a horizontal line lying in the roof surface, and the top and bottom marginal edges of each unit being parallel and at an oblique angle to the side edges, said oblique angle being such that when the units are in- 115 120 125 130

terlocked, these units extend in a direction parallel to a line at right angles to the side marginal edges of said units.

7. A roofing shingle comprising a central section, marginal sections folded over said central section, said folds being such as to permit interlocking a plurality of shingles, and a tile secured to the central section.

8. A roofing shingle comprising a central section, marginal sections folded over said central section, and a tile secured to the central section, some of the marginal sections on the edges of the central section being folded over on one side thereof, and the other marginal section being folded over the other side thereof.

In testimony whereof, I have subscribed my name.

THEODORE C. PROUTY.
